UNITED STATES PATENT OFFICE.

HENRY M. BYLLESBY, OF PITTSBURG, PENNSYLVANIA, ASSIGNOR TO
GEORGE WESTINGHOUSE, JR., OF SAME PLACE.

ELECTRIC CONVERTER.

SPECIFICATION forming part of Letters Patent No. 366,375, dated July 12, 1887.

Application filed January 10, 1887. Serial No. 223,871. (No model.)

To all whom it may concern:

Be it known that I, HENRY M. BYLLESBY, a citizen of the United States, residing in Pittsburgh, in the county of Allegheny and 5 State of Pennsylvania, have invented certain new and useful Improvements in Electric Converters, of which the following is a specification.

The invention relates to the construction of 10 induction-coils or electric converters, and especially to that class of converters in which a core is made up of thin sheets of soft iron formed with rectangular openings through which the coils extend.

15 The object of the invention is to insure that the coils shall be thoroughly insulated from each other, and also from the surrounding iron. To this end the primary and secondary coils are separately wound and wrapped with 20 suitable insulating material, and they are separated from each other a slight distance by suitable insulating material—such, for instance, as leatheroid or white fiber. Narrow strips of the same material are preferably placed 25 between the remaining sides of the coils and the surrounding metal.

In the accompanying drawings, Figure 1 is 30 a section of a converter constructed upon the principle of this invention; and Fig. 2 is a side view of the same.

Referring to the figures, P represents the primary and S the secondary coil of an electric converter. These coils are separately wound, and are then covered with suitable 35 non-conducting material—such, for instance, as bands of cotton cloth or canvas wound upon them and coated with shellac or other non-conducting material. The coils are then placed side by side, being separated by strips 40 or plates of leatheroid or white fiber or other suitable non-conducting substance, as shown at a. Narrow strips of the same material are bound against the sides of the coils, as shown at a' a'. The core of soft iron is then applied.

This core is preferably built up of thin sheets 45 of soft iron, (shown at b,) the plates being preferably formed with rectangular openings slightly larger than the coils, thus allowing for the space occupied by the strips a' a' and intervening air-spaces for cooling and ventilation. The plates are cut open, as shown at e' e', and the sides e' e' are bent back temporarily to allow the central tongue, f, to be inserted within the coils. This form of core is described in an application for Letters Patent filed by Albert 50 Schmid December 27, 1886, and no claim is herein made upon the construction of the core itself.

I claim as my invention—

1. The combination, with the primary and 60 secondary coils of a converter, separately wound and covered with insulating material, of plates of non-conducting material between said coils, strips of non-conducting material extending along the sides of the coils, and a 65 core of soft iron surrounding the coils, leaving air-spaces between said strips.

2. In an electric converter, the combination, with the primary and secondary coils separately wound, of plates of insulating material 70 between the coils and strips of insulating material extending along the sides of the coils and separating the same from the surrounding core, substantially as described.

3. The combination, in an electric converter, 75 of a core built up of plates or sheets of soft iron magnetically insulated from each other, and having rectangular openings, primary and secondary coils within said openings, and strips 80 of insulating substance separating the coils from the core, substantially as described.

In testimony whereof I have hereunto subscribed my name this 8th day of December, A. D. 1886.

HENRY M. BYLLESBY.
